UNITED STATES PATENT OFFICE.

WILLIAM J. ROA, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

FLOOR AND WALL CONNECTION FOR RAILWAY-CARS.

1,224,790.

Specification of Letters Patent.

Patented May 1, 1917.

Application filed November 18, 1915. Serial No. 62,081.

To all whom it may concern:

Be it known that I, WILLIAM J. ROA, a citizen of the United States, residing at St. Louis, Missouri, have invented a certain new and useful Improvement in Floor and Wall Connections for Railway-Cars, of which the following is a full, clear, and exact description, such as will enable others skilled in the art to which it appertains to 10 make and use the same, reference being had to the accompanying drawings, forming part of this specification.

My invention relates generally to the combination of railway cars and particularly 15 those cars which are utilized for carrying grain, the principal object of my invention being to provide a comparatively simple and effective joint or connection between the side wall and floor of the car, which joint or 20 connection in addition to being weather and dust proof, will be effective in preventing the leakage of grain, even though the flooring and lower portion of the side wall sheathing tend to spread apart or separate 25 as a result of shrinkage of the wood, or by reason of service strains.

The flooring and side wall sheathing of grain carrying cars are usually constructed of comparatively thick lumber and when the 30 same dries out there is a tendency of the wood to shrink, thereby opening the joint between said flooring and wall sheathing, which action permits leakage of grain through the open joint, and this loss is 35 chargeable to the railway or transportation company owning the car. In some instances, metal joint members have been utilized between the flooring and side wall sheathing, but such construction is objectionable for 40 the reason that the moisture which collects upon the metal joint member is injurious to a considerable portion of the grain forming the lading of the car or that portion which occupies the corner between the floor- 45 ing and wall sheathing.

I propose to overcome the objectionable results just noted, by providing a member which, in addition to serving as the side sill of the car underframe and a support for the 50 ends of the floor boards and the wall sheathing, provides means which cooperate with the lower portion of the sheathing to form an effective grain tight and dust and moisture proof joint between said sheathing and 55 floor boards, said means being located ex-

teriorly of the sheathing and at a point where it cannot contact with the grain forming the lading of the car.

A further object of my invention is to provide a grain tight and dust and moisture 60 proof joint between the lower portion of the wall sheathing and the car flooring which will permit the ready removal of the floor boards, without disturbing the wall sheathing and which joint can be formed 65 without the necessity of rabbeting or grooving the lower sheathing member or the floor boards.

A further object of my invention is to provide the side sill member with an up- 70 standing flange of substantial width, the same not only serving to prevent the lower member of the side wall from bulging outwardly from the sill between the framing members, but providing ample riveting area 75 for the framing members, thereby avoiding the necessity of providing extra gusset plate connections and the expense incident to the use thereof. By my improved construction it is possible to utilize a comparatively thin 80 wall member between the upstanding flange on the side sill and the ends of the floor boards, thus avoiding the necessity of rabbeting the lower one of the wall boards and permitting the outer face of the side sill and 85 the outer faces of the side wall members above the comparatively thin lower wall member to lie flush with the inner faces of the framing members.

With the foregoing and other objects in 90 view, my invention consists in certain novel features of construction and arrangement of parts, hereinafter more fully described, claimed and illustrated in the accompanying drawings, in which— 95

Figure 1 is a perspective view of a metal beam contemplated by my invention and which serves as a combined side sill and joint forming member.

Fig. 2 is a detail section taken vertically 100 through the lower corner of a car and showing the joint between the floor and sheathing as contemplated by my invention.

Fig. 3 is a side elevational view of a portion of the combined side sill and joint forming member contemplated by my invention 105 and showing the lower portion of a side post connected thereto.

Fig. 4 is a sectional view of the side sill and joint forming member, said view being 110

taken at a point beneath the side door of the car.

The combined side sill and joint forming member contemplated by my invention comprises a commercially rolled metal shape in the form of a channel having the usual web 10 and substantially parallel top and bottom flanges 11. This channel-shaped member serves as the side sill of the car under frame and, when properly positioned, the flanges 11 are inwardly presented as seen in Fig. 2.

Formed integral with the top of the sill member and preferably in alignment with the web 10 is an upstanding flange 12, the same being several inches in height so as to provide a broad substantial bearing for the lower one of the wall members. This flange with the upper one of the flanges 11 forms an angle at the top of the side sill and said angle in addition to serving as a support for the ends of the floor boards and the wall sheathing, combines therewith to form a grain tight and dust and moisture proof joint.

The wall sheathing 13 is of the usual matched tongue and groove type and the lower one 13^a of the sheathing members or the one which rests directly upon the upper flange 11 and against flange 12 is slightly thinner than the members forming the main body portion of the wall. Thus the outer face of the wall is substantially flush with the outer faces of flange 12 and web 10, and the inner faces of the side framing members lie flush with or directly against the outer faces of said web 10, flange 12 and the comparatively thick wall members 13 positioned above the lowermost thin wall members 13^a.

The ends of the floor boards 14 rest on top of the upper one of the flanges 11 and bear directly against the inner face of the lower one 13^a of the sheathing members, said floor boards being secured to said upper flange in any suitable manner, preferably by means of bolts 15.

By utilizing a comparatively thin wall member at the bottom of the wall, the necessity of rabbeting one of the comparatively thick wall members is avoided.

At the side door of the car the upstanding flange 12 is slotted vertically at points adjacent to the door posts and that portion of the flange between said slots is bent downward into a substantially horizontal plane as designated by 12^a in Fig. 4, thus forming a support for the extended ends of the floor boards.

The usual cross bearers 16 lie beneath and are fixed to the lower portions of sills 10 in any suitable manner, preferably by means of rivets 16^a, and the usual side posts 17 are secured to the sills 10 and flanges 12 by means of rivets 17^a and to the ends of the cross bearers by rivets 17^b. The lower end

of the usual side wall braces 18 are secured to the sill 10 and flange 12 in any suitable manner, preferably by means of rivets 18^a.

The top flange of the sill member and the up-standing flange 12 combine to form an externally arranged angle at the corner between the car flooring and side wall sheathing and in addition to supporting said parts and holding same in proper relative positions, serves to prevent the ingress of moisture and dust, and likewise the egress of grain in the event that the flooring and sheathing tend to shrink away from each other due to drying out or in the event that said parts are pulled apart as a result of service strains due to vibration, shifting loads, and the like.

Inasmuch as the upper one of the flanges 11 and flange 12 are externally located with respect to the flooring and wall sheathing, the grain forming the lading of the car cannot come in contact with said flanges, and, therefore, said grain will not be affected by moisture which under certain atmospheric conditions collects on exposed metal.

A combined sill joint forming member of my improved construction is comparatively simple, serves as a support and protection for the ends of the floor boards and the lower one of the sheathing members of the wall, and combines with said parts to form a grain-tight, and moisture and dust proof joint.

The comparatively wide flange 12 provides ample riveting area for the side framing members, thereby doing away with the necessity of providing extra gusset plates or the like and said side flanges also maintains the comparatively thin lower wall member 13^a in position against the ends of the floor boards 14 and effectively prevents said lower wall member from bulging outwardly between the framing members.

It will be readily understood that minor changes in the size, form and construction of the various parts of my improved device can be made and substituted for those herein shown and described, without departing from the spirit of my invention, the scope of which is set forth in the appended claims.

I claim:

1. In car construction the combination with a sill member having a wide upstanding flange formed integral with its upper outer corner, of flooring supported by the upper portion of said sill member, and wall sheathing, the lower member of which is thinner than the upper members and is interposed between the edge of the flooring and said up-standing flange.

2. In car construction, the combination with a sill member having a wide up-standing flange formed integral at its upper outer corner, and wall sheathing, the lower member of which is thinner than the upper

members and bears on said sill member and against the up-standing flange thereon.

3. In car construction, the combination with a sill member having a wide up-standing flange formed integral at its upper outer corner, wall sheathing, the lower member of which is thinner than the upper members and bears on said sill member and against the up-standing flange thereon, and car 10 flooring supported by said sill member with the edge of said flooring terminating adjacent to the inner face of the wall sheathing.

4. In car construction, the combination with a sill member having a wide up-standing flange formed integral at its upper outer corner, wall sheathing, the lower member of which is thinner than the upper members and bears on said sill member and against the up-standing flange thereon, and car 15 flooring supported by and fixed to said sill member with the edge of said flooring terminating adjacent to the inner face of the wall sheathing.

5. In car construction, an underframe side 25 sill member provided with a wide integral upwardly projecting combined riveting flange and wall sheathing engaging member.

6. In car construction, the combination with a sill member having a wide up-standing flange formed integral at its upper outer corner, of wall members, the lower one of which is thinner than the upper ones and bears directly on the sill member against the upstanding flange thereof, the outer 35 faces of said sill member and the flange thereon and the outer faces of the wall members above the narrow lower member occupying the same vertical plane.

7. In car construction, an underframe side 40 sill member provided with an integral upwardly projecting wall sheathing engaging member, a portion of which last mentioned member is bent downward into a substantially horizontal plane and serves as a support for the extended ends of the car 45 flooring boards.

8. In car construction, the combination with a sill member having an up-standing flange at its upper outer corner, of flooring 50 supported by the upper portion of said sill member, wall sheathing, the lower portion of which is positioned between the flooring and the up-standing flange, and a portion of which flange is bent into a substantially 55 horizontal plane to form a support for an extended portion of the flooring.

9. In car construction, the combination with a sill member having an up-standing flange formed at its upper outer corner, wall 60 sheathing, the lower portion of which is supported by said sill member and bears against the up-standing flange thereupon, a portion of which up-standing flange is bent into a substantially horizontal plane, and 65 flooring supported by said sill member and

the horizontally disposed portion of said flange.

10. In car construction, an underframe side sill member provided with an integral upwardly projecting wall sheathing engaging member, a portion of which member is bent out of its normal plane to form a support for the extended ends of the car 70 flooring boards.

11. In car construction, an underframe side 75 sill member comprising a beam which is channel shape in cross section, a wide vertically disposed flange formed integral with the upper outer corner of said beam, said flange occupying substantially the same vertical plane with the web of the beam wall sheathing, the lower member of which rests on the side sill and bears against the wide vertically disposed flange, and side posts and side braces, the lower portions of which 80 are riveted to the sill member and to the vertically disposed flange.

12. In car construction an underframe side sill member provided with an integral upwardly projecting wall sheathing engaging member and with a horizontally disposed flange which is adapted to serve as a support for the extended ends of the car 90 flooring boards said upwardly projecting member serving as a riveting flange for the lower portions of the car, side posts and side 95 braces.

13. In car construction, an underframe side sill member having integral portions which are adapted to engage the car wall 100 sheathing, and an integral outwardly projecting portion which serves as a support for the extended ends of the car flooring boards.

14. In car construction, the combination with a sill member having a wide up-standing flange formed integral at its upper outer corner, wall sheathing, the lower member of which is thinner than the upper members and bears on said sill member against the upstanding flange thereon, car flooring supported by said sill member, the edge of which flooring terminates adjacent to the inner face of the lower wall member and side framing members bearing directly against the outer faces of the sill member, the upstanding flange thereon and the upper wall members the lower portions of which side framing members are rigidly fixed to the sill member and the upstanding flange 110 thereon. 115

15. In car construction, the combination with a sill member having a wide up-standing flange formed integral at its upper outer corner, wall sheathing, the lower member of which is thinner than the upper members 125 and bears on said sill member against the upstanding flange thereon, car flooring supported by said sill member, the edge of which flooring terminates adjacent to the inner face of the lower wall members, side 130

framing members bearing directly against the outer faces of the sill member, the upstanding flange thereon and the upper wall members, and fastening means seated in said 5 framing members, the sill member and the upstanding flange thereon.

In testimony whereof I hereunto affix my

signature in the presence of two witnesses, this first day of November, 1915.

WILLIAM J. ROA.
